STORM WINDOW

Filed Feb. 1, 1929

INVENTOR
WILLIAM C. LEBER

BY *James H. Jones*
ATTORNEY

UNITED STATES PATENT OFFICE

WILLIAM C. LEBER, OF FARGO, NORTH DAKOTA

STORM WINDOW

Application filed February 1, 1929. Serial No. 336,677.

One object of my said invention is the provision of a storm window including a main frame, fixed glasses therein, a glass adapted to be slidably moved for the admission or exclusion of air, and a frame fixed in the main frame and complementary to and adapted for the strong weather-tight holding and free movement of the slidable glass.

Another object is the provision of a storm window the main frame of which is adapted to be conveniently opened and closed, and is equipped with simple and inexpensive means for efficiently packing the main frame when closed with a view to excluding the weather.

15 To the attainment of the foregoing the invention consists in the improvement as hereinafter described and definitely claimed.

In the accompanying drawings, forming part of this specification:

20 Figure 1 is an elevation, partly in section, of the inner side of the storm window constituting the preferred embodiment of my invention.

Figure 2 is a vertical section showing my 25 novel window as properly positioned and fastened in a conventional window frame, the section through the storm window being in the plane indicated by the line 2—2 of Figure 1.

30 Figure 3 is a section through the storm window per se on the line 3—3 of Figure 1.

Figure 4 is a fragmentary section showing a portion of the slidable glass, its marginal frame, and the fixed frame in which said 35 marginal frame is disposed and slidable.

Similar numerals of reference designate corresponding parts in all of the views of the drawings.

The conventional window frame 1 is shown 40 as containing sliding sashes 2 and 3, and a bead 4 at the outer side of the outer sash 3.

Eyes 5 are connected to the sill 6 of the frame 1, and hooks 7 are provided at the outer side of the crown portion of the same.

45 My novel storm window per se includes among other elements a main frame 8, preferably of wood, and equipped with hooks 9 to engage the said eyes 5, and with eyes 10 to engage the said hooks 7, Figure 2. In the 60 inner side of the frame 8 near the edge there-

of is a groove 11 which in cross-section describes slightly more than half of a circle, and in said groove is held a packing or weather strip of tubular rubber or of felt or other suitable material adapted when the frame 8 is fastened in closed position, Figure 2, to engage the face of the bead 4 and thereby exclude the weather.

In addition to the elements named, the storm window constituting the preferred embodiment of my invention includes fixed glasses 12, 13 and 14, spaced bar portions 14* between the glass 14 and an opening 15* through the sash, an open, rectangular metallic frame 15, of channel cross-section, fixed in the main frame 8 and extending through the space between said bar portions 14* and arranged in a vertical plane alongside the vertical plane of the glass 14, Figure 3 and extending practically the full width of the main frame 8, 70 a slidable glass 16, and a marginal metallic frame 17, of channel cross-section, straddling the edge of the glass 16 and snugly fitting and slidable in the frame 15 from and to the fully-closed position shown in Figures 1 and 3. On 75 the said frame 17 is a finger piece 18, Figure 1, to facilitate the sliding of the glass 16 to open and closed positions.

Manifestly when the glass 16 is positioned as shown in Figures 1 and 3, the storm window will efficiently bar the passage of air, one bar of the frame 17 resting in the space between the bar portions 14*, Figure 3. When, however, said glass 16 is slidably moved to a position alongside the fixed glass 14, the opening 15* for ventilating purpose will be left unobstructed in the storm window; and it will also be noticed that the glass 16 may be opened to the full or less extent according to the size of opening desired.

Having described my invention, what I claim and desire to secure by Letters Patent is:

1. A storm window comprising a main frame, a fixed glass therein, spaced bar portions fixed in the main frame at the inner edge of said glass, an open, rectangular metallic frame of channel cross-section fixed in the main frame and extending alongside of and beyond the fixed glass and through the space 100

between said bar portions, a glass slidable in the fixed metallic frame through said space to and from a position alongside the fixed glass, and a marginal metallic frame of channel cross-section on the edge of the slidable glass and snugly fitting and movable in the fixed metallic frame, one bar of said frame resting in the space between the bar portions when the slidable glass is in working position.

- 5 2. In combination a window frame, sash therein, a bead in said frame outwardly beyond the sash, hooks on the outer side of the upper portion of the window frame, a swingable storm window having transparent means and also having eyes engaged with said hooks, means for detachably securing said storm window in closed position, and packing held in a groove in the inner side of the storm window and extending entirely around said transparent means and projecting from said side and adapted when the storm window is closed to bear against said bead.
